WALL PLAQUE OR SIMILAR ARTICLE

Berma Bjorklund, Spokane, Wash.

Application August 29, 1955, Serial No. 37,683

Term of patent 14 years

(Cl. D29—23)

FIG. 2

Fig. 1 is a front elevational view of a wall plaque or similar article, showing my new design; and

Fig. 2 is a left side view as seen from a vantage point slightly above and to the left of Fig. 1.

The back surface is plain.

I claim:

The ornamental design for a wall plaque or similar article, substantially as shown and described.
